UNITED STATES PATENT OFFICE.

MAURICE GALLET AND ADOLPH B. ANDERSON, OF POUGHKEEPSIE, NEW YORK.

AEROPLANE.

Application filed July 28, 1927. Serial No. 209,044.

The present invention relates to improvements in aeroplanes and has for its principal object to provide a structure which offers the least resistance in passing through the air and uses the currents of air to assist in the buoyancy of the aeroplane, while flying and to develop energy for electric or other motors.

Another very important object of the invention resides in the provision of an aeroplane having a body constructed with tubular members extending longitudinally thereof and propellers mounted in the front of the tubular members and turbines in the rear portions thereof.

A still further very important object of the invention resides in the provision of an aeroplane of this nature, which is comparatively simple in its construction, thoroughly efficient and reliable in operation, easy to manoeuvre and otherwise well adapted to the purpose for which it is designed.

A still further very important object of this invention resides in the provision of using current of air through tubes, when plane is flying, to drive turbines coupled with electric generators or other devices furnishing power for forward engines.

With the above numerous other objects in view, as will appear as the descriptions proceed, the invention resides in certain novel features of construction, and in the combination and arrangement of parts as will be hereinafter more fully described and claimed.

In the drawings:—

Figure 1 is a top plan of an aeroplane embodying the features of our invention, showing portions thereof broken away.

Figure 2 is a longitudinal vertical section therethrough.

Figure 3 is a front elevation thereof.

Figures 4 and 5 are diagrammatic front elevations showing different forms of tubes which may be used.

Figures 6 and 7 are diagrammatic longitudinal views of tubes showing different turbine structure which may be used.

Figure 8 is a view similar to Figure 1 showing a generator, and

Figure 9 is a longitudinal section therethrough.

Referring to the drawings in detail, and especially the embodiment shown in Figures 1 to 3, inclusive, it will be seen that the body of the aeroplane comprises a longitudinal

central portion 5 having vertical passages 6 therethrough, and a pair of tubes 7, one to each side of the central portion 6, extending longitudinally thereof. Wings 9 project laterally from the body, one to each side thereof and have tubular passages 10 extending longitudinally therethrough. In the front of each tubular member 7 there is mounted a prime mover 11, for operation of a propeller 12. In the rear portion of each tubular side member 7 of the body, there is formed a depression 14, in the bottom, and a shaft 15 is journaled so that blades 16 coupled with generator move in the depression 14 and in the passage through the tubular member. Figure 6 it is shown that the tubular members 7 may be flared at their front ends and in the rear have the turbines, both at the top and at the bottom in suitable compartments 75 for that purpose. In Figure 7 it is shown that the tubular members 7 may have depressions 19 and have turbine structures 20 mounted therein to be propelled by the air passing through the tubes for the purpose of operating any suitable mechanism for the purpose of generating power for the forward engines.

In Figure 4, it is shown that the portions of the body may be circular. In Figure 5 it is shown that the body members may be oval shaped and the wing structures may be formed of a plurality of cylindrical tubes.

It will be seen that an aeroplane constructed in accordance with this invention will bear little resistance to flying through the air and the arrangement of the propelling means in the tubular portion of the body will greatly assist in the forward propulsion thereof.

In the vertical passages 6 of the central portion 5 it will be seen that the propellers 20 are mounted for assisting in lifting the aeroplane from the ground and while in flight.

In Figures 8 and 9 we have shown an embodiment of the invention very similar to that included in Figure 1, but in the center have shown a generator 30 operated by a propeller 31.

It is thought that the construction, operation, and advantages of this invention will now be quite apparent without a more detailed description thereof. It will be seen that the principles of the invention may be embodied in ground vehicles and in boats. The present embodiment of the invention

has been disclosed in detail, merely by way of example, since in actual practice it attains the features of advantage enumerated as desirable in the statement of the invention and the above description.

It will be apparent that changes in the details of construction and in the combination and arrangement of parts may be resorted to, without departing from the spirit or scope 10 of the invention as hereinafter claimed or sacrificing any of its advantages.

Having thus described the invention, what we claim is:—

- 15 1. In an aeroplane, a body comprising a pair of longitudinally extending tubular side members, the bottoms of which adjacent their rear ends are depressed, to form compartments and turbines journaled in the side members so that their blades move longitudinally of the side members and in the compartments, being actuated by currents of air through the side members.
- 20 2. In an aeroplane, a body comprising a pair of longitudinally extending tubular side members, the bottoms of which adjacent

their rear ends are depressed, to form compartments and turbines journaled in the side members so that their blades move longitudinally of the side members and in the compartments, being actuated by currents of 30 air through the side members, propeller means in the forward ends of the side members.

3. In an aeroplane, a body comprising a pair of longitudinally extending tubular side 35 members, the bottoms of which adjacent their rear ends are depressed, to form compartments and turbines journaled in the side members so that their blades move longitudinally of the side members and in the 40 compartments, being actuated by currents of air through the side members, propeller means in the forward ends of the side members, a central member between the side member and formed with vertical passages, 45 and propellers in the vertical passages.

In testimony whereof we affix our signatures.

MAURICE GALLET.
ADOLPH B. ANDERSON.
